REFRIGERATED DISPENSER CABINET FOR BEVERAGES OR THE LIKE

James R. Reichow, Edina, Minn., assignor to The Cornelius Company, Anoka, Minn., a corporation of Minnesota

Filed May 26, 1964, Ser. No. 80,150

Term of patent 14 years

(Cl. D67—3)

FIG. 1 is a perspective view taken from the front and one side of a refrigerated dispenser cabinet for beverages or the like showing my design.

FIG. 2 is an elevational view taken from the side opposite that shown in FIG. 1.

FIG. 3 is a rear elevational view thereof.

FIG. 4 is a top plan view thereof.

The stippling on the door as shown in FIGS. 1, 2 and 4 represents grained leather, the cross lines on the lower part of the door as shown in FIGS. 1 and 2 represent a conventional grill, and the lined shading on the side panels as shown in FIGS. 1 and 2 represents wood grain.

I claim:

The ornamental design for a refrigerated dispenser cabinet for beverages or the like, substantially as shown and described.
